L. A. TURNER

SPADE LUG FOR TRACTOR WHEELS

Filed August 11, 1924

UNITED STATES PATENT OFFICE.

LEONARD A. TURNER, OF SANTA ANA, CALIFORNIA.

SPADE LUG FOR TRACTOR WHEELS.

Application filed August 11, 1924. Serial No. 731,443.

To all whom it may concern:

Be it known that I, LEONARD A. TURNER, a citizen of the United States, residing at Santa Ana, in the county of Orange and 5 State of California, have invented new and useful Improvements in Spade Lugs for Tractor Wheels, of which the following is a specification.

This invention relates to improvements in 10 spade lugs for tractor wheels.

It is an object of the invention to provide an improved traction device adapted to be secured upon the periphery of the tractor wheel.

15 Another object of the invention is to provide an improved device for the above stated purpose which has an adjustable shoe or ground engaging member, such that the shoe may be adjusted with respect to the rim of 20 the tractor wheel to take up wear.

Another object of the invention is to provide a traction device which has an adjustable shoe to take up wear and which shoe is capable of being reversed so that when 25 one side of the shoe is worn, the other side may be employed as the ground engaging portion, thereby prolonging the life of each shoe.

A still further object of the invention is 30 to provide an adjustable shoe of such shape that sticky or damp soil will not have a tendency to collect upon the face or rim of the wheel as has been experienced upon prior devices of this character.

35 Still further objects reside in forming a traction device attachable to a tractor wheel which is made of two pieces, one of which consists of the wearing shoe which is relatively simple and inexpensive, thereby providing cheap replacement. Also, it is an object to provide the adjustable shoe of the device with a fine adjustment so that the shoe may be adjusted relatively to the wheel suitable to various soil conditions.

45 With the foregoing and other objects in view which will be pointed out in the following detailed description and defined in the appended claims, reference is had to the accompanying drawing for an illustrative embodiment of the invention in its preferred form, wherein—

Fig. 1, is a partial side elevation of a portion of a tractor wheel upon which the improved traction device is mounted.

55 Fig. 2, is a section taken through Fig. 1, substantially on the line 2—2 thereof.

Fig. 3, is a section also taken through Fig. 1, substantially upon the line 3—3 thereof.

Fig. 4, is a vertical section taken through Fig. 2, substantially on the line 4—4, the ground engaging shoe being shown as originally applied.

Fig. 5, is a similar view to Fig. 4, the ground engaging shoe being shown as having been adjusted to take up wear. 65

Fig. 6, is a view similar to Figures 4 and 5, the ground engaging shoe being shown as having been reversed after one side has been completely worn.

Figures 7 and 8, are perspective views of 70 the mounting or supporting member of the device.

Fig. 9, is a perspective view of the ground engaging shoe.

Fig. 10, is a section taken substantially on 75 the line 10—10 of Figure 9.

Referring to the accompanying drawing wherein similar reference characters designate similar parts throughout, the device in its preferred embodiment consists of a 80 mounting member somewhat L shaped in cross section, which consists of a bottom 10, adapted to be secured to the rim 11, of a tractor wheel by means of bolts 12, extending therethru. The mounting member 10, 85 is preferably a single casting which may be of cast iron, cast steel, or forged steel and has integral with the bottom 10, an inclined face 13, and somewhat triangular shaped sides 14 and 15, joining the inclined face 13, 90 with the bottom 10. As clearly shown in Fig. 2, the base 10, has a flange or lip 16, beneath one of the sides which is adapted to extend over the edge of the rim or face of the wheel 11, and snugly bear thereagainst. The inclined face 13, has a slot or elongated opening 17, through which is 95 adapted to pass the shank of the bolt 18. A series of projecting teeth 19, project from the front face of the inclined face 13. 100

The head 20, of the bolt 18, is received within a socket 21, of the ground engaging shoe 22, which shoe has upon its rear face a series of teeth 23, adapted to interfit with the teeth 19. A nut 24, which bears against a lock washer 25, serves to tighten the bolt 18, and hold the ground engaging shoe 22, with its teeth 23, in interfitting engagement with the teeth 19. The ground engaging shoe 22, has a pair of side flanges 26, which 110 are adapted to bear against the sides 14 and 15.

Adjustment for the device is provided by unscrewing the nut 24, so that the teeth 23, of the ground engaging shoe 22, may slide over the teeth 19, so that as the upper edge 5 of the shoe 22, as shown in Fig. 4, becomes worn, the shoe may be raised one or more teeth at a time and clamped in such position by means of the bolt 18.

This adjustment may be made either when 10 the shoe becomes worn or upon using the tractor upon very soft ground where a longer or deeper traction device is desired.

The bolt 18, is slidable within the slot 17, and in Fig. 5, the shoe is shown as having 15 been worn and raised into its uppermost position with the bolt 18, engaging the upper surface of the slot 17. In Fig. 6, the shoe 22, is shown as having been reversed after one-half of the shoe has been worn 20 off, so that the opposite or unused half may be worn before replacement of the shoe is necessary.

As clearly shown in Fig. 10, the shoe 22, has its exposed face transversely curved 25 which has been found by experiment will provide a surface, because of its curvature will not have the tendency to allow mud or sticky soil to cake and collect thereon.

From the above, it is seen that I have provided a traction device for tractor wheels, having a mounting member provided with an inclined face, teeth arranged upon the inclined face and a shoe which is adjustable 30 and which is reversible, removably secured upon the inclined face.

It is to be understood that various changes may be made in the details of construction without departing from the spirit or scope of the invention as defined by the 40 appended claims.

What I claim is:

1. A traction device for tractor wheels, comprising a mounting member attachable to the rim of a tractor wheel, said mounting member having a flange adapted to bear upon the edge of the tractor wheel and an adjustable shoe secured upon said mounting member.

2. A traction device for tractor wheels, comprising a mounting member adapted to be secured upon the rim of a tractor wheel, said mounting member having an inclined face and a shoe adjustably secured against the inclined face of said mounting member.

3. A traction device for tractor wheels, comprising a mounting member attachable to the rim of a tractor wheel, said mounting member having a flat face, teeth ar-

ranged upon said flat face and an adjustable shoe having teeth adapted to interfit with the teeth upon the mounting member, said shoe being removably secured to said mounting member.

4. A traction device for tractor wheels, comprising a mounting member adapted to be secured to the rim of a tractor wheel, said mounting member having an inclined face, teeth formed upon said face, a shoe having teeth adapted to interfit with the teeth upon said mounting member, said shoe being removably secured to said mounting member.

5. A traction device for tractor wheels, comprising a mounting member adapted to be secured to a tractor wheel, said mounting member having an inclined flat face, teeth arranged upon the flat face of said mounting member, a shoe having teeth adapted to interfit with the teeth upon said mounting member, said shoe having lateral flanges adapted to bear against the sides of the mounting member, and means for removably and adjustably securing said shoe upon said inclined face.

6. A traction device for tractor wheels, comprising a mounting member attachable to the rim of a tractor wheel, said mounting member having a lateral flange adapted to engage the edge of said rim, an inclined face formed upon said mounting member and having teeth, a reversible shoe having teeth adapted to interfit with the teeth of said inclined face, and means for adjustably and removably securing said shoe upon said mounting member, said shoe having its exposed face transversely curved.

7. In a traction device for tractors, a removable shoe having a transversely curved exposed face, and a lateral bearing flange at each side thereof.

8. A traction device for tractor wheels comprising a mounting member adapted to be mounted upon the exterior peripheral surface of a tractor wheel, said mounting member having a plurality of teeth formed thereon, a shoe having complementary teeth formed thereon, and means for securing said shoe to said mounting member.

9. A removable shoe for traction devices for tractor wheels having a plurality of transverse teeth formed upon its under side, and a lateral bearing flange at each side thereof.

In testimony whereof I have signed my name to this specification.

LEONARD A. TURNER.
